Francis Parker,

UNITED STATES PATENT OFFICE.

FRANCIS PARKER, OF WESTON, MASSACHUSETTS.

WATCH-BARREL.

SPECIFICATION forming part of Letters Patent No. 364,370, dated June 7, 1887.

Application filed December 20, 1886. Serial No. 222,056. (No model.)

To all whom it may concern:

Be it known that I, FRANCIS PARKER, of Weston, in the county of Middlesex and State of Massachusetts, have invented a new and useful Improvement in Watch-Movements, of which the following is a specification.

My invention relates to watch-movements in which the main wheel is carried directly by the barrel containing the mainspring. Watches so constructed have the barrel and main wheel rigidly fastened together, so that any motion imparted to the barrel is likewise imparted to the main wheel, by which wheel motion is transmitted to the rest of the watch-movement, and when the mainspring breaks, the motion of the barrel being suddenly reversed reverses the motion of the main wheel and the train of gears driven by it, often causing injury to some of the other parts of the watch-movement. The object of my invention is to prevent such injury to the movement of the watch. I effect this object by separating the main wheel from the barrel and connecting them by a pawl and stop, which compel the main wheel to turn with the barrel when the barrel rotates in one direction and allow the main wheel to be at rest when the barrel rotates in the reverse direction.

In the drawings, Figure 1 shows in elevation the main wheel and barrel containing my invention and connecting parts, partly in section. Fig. 2 shows a section through the barrel and main wheel, on the line $\alpha\alpha$ of Fig. 1, and the arbor in elevation. Fig. 3 shows an inverted plan of the bottom plate of the barrel, the stop on the main wheel, against which the pawl on the barrel normally bears, being indicated by the circle of broken lines.

The drawings are on an enlarged scale.

G is the main wheel, which has the raised rim M and teeth T, and engages with the pinion W of the center wheel. O is a stop on the main wheel, against which the pawl P on the under side of the bottom plate, R, of the barrel B normally bears.

S is a stud upon which the pawl P turns, and Y another stud, against which the pawl-spring I of the pawl P abuts. The main wheel G has the back-tapered hub H, which has the shoulder E. The barrel B fits into the main wheel G, its shoulder U resting upon the rim

M of the main wheel and the opening N in its bottom plate, R, allowing the hub H of the main wheel to pass into the barrel B, as shown. A spring-ring, L, its rim cut through at one point to allow the ring to be opened, that it may be placed around the hub H above the shoulder E of the hub, extends into the sunk rim V, which surrounds the opening N in the bottom plate, R, of the barrel, and locks the barrel and main wheel together, but does not bind them rigidly together, the barrel being left free to revolve independently of the main wheel when the pawl P does not bear against the stop O.

Q is the mainspring, one end of which is attached to the barrel-arbor A and the other end to the barrel B. The arbor is held in place between the hub H of the main wheel and the cap C of the barrel B, and passes through the hub and carries on its lower end a ratchet-wheel, which is prevented from turning back by a click. The arbor A also passes through the cap C, and is shown in the drawings squared at its upper end to admit of winding with a key.

The operation is as follows: When the watch is wound up, the mainspring is coiled upon the arbor. The mainspring as it uncoils drives the barrel. The pawl on the bottom plate of the barrel bears against the stop on the main wheel and causes the barrel to take with the main wheel and the main wheel to act thereby with the barrel and drive the center wheel, which latter wheel transmits motion to the rest of the watch-movement. When the mainspring breaks and the motion of the barrel is suddenly reversed, the barrel gives to any motion reverse to the direction of motion to the watch-movement, the barrel acting independently of the main wheel, whereby the reverse motion is taken by the barrel and is not communicated to the main wheel, and consequently is not transmitted to the rest of the movement of the watch, the pawl-spring giving sufficiently to allow the pawl to pass the stop on the main wheel and the barrel to continue its reverse motion independently of the main wheel until the reverse motion is spent.

I claim—

1. In a watch, the combination, with the

barrel, arbor, and mainspring, of the main wheel G, stop O, and pawl P, substantially as described, for the purpose specified.

2. A device for locking together a separate barrel and main wheel of a watch, such that it shall not lock them rigidly, consisting of the back-tapered hub H of the main wheel having a shoulder, E, and extending into the barrel,

and a ring, L, placed about said hub above said shoulder and extending into the sunk rim ^{to} V of the bottom plate of the barrel, substantially as described.

FRANCIS PARKER.
